AIR CONDITIONING APPARATUS

Norman H. Gay, Los Angeles, Calif.

Application August 15, 1935, Serial No. 36,396

7 Claims. (Cl. 62—6)

This invention relates to improvements in air-conditioning apparatus, and particularly concerns means for removing humidity from the air while it is being circulated to and from the apartment.

One of the features of the present invention is the provision of devices operating to provide a circulation of a heat-exchanging medium which is employed for pre-cooling the air preparatory to a secondary cooling operation, and for re-heating the air following such secondary cooling thereof.

Another feature of the present invention is the provision of a refrigerating plant for establishing a cooling effect upon the air, and comprising an evaporator disposed in the path of the air movement, in conjunction with a condenser for the refrigerant gas and means for raising the gas upon its return from the evaporator to a suitable pressure, together with means located in the conduit from the condenser to the evaporator for producing a sub-cooling effect upon the liquid and thereby producing a heating effect upon the air.

Another feature of the present invention is the provision of a refrigerating plant including an evaporator and a conduit leading from the evaporator to pressure producing means, this conduit including devices located in the path of the air movement for causing a cooling of the air on its way to the evaporator for a further cooling at said evaporator.

A further feature of the present invention is the provision of a refrigerating plant including an evaporator for producing a cooling of the air to a pre-determined minimum temperature, together with means traversed by the refrigerant medium on its way from and to the evaporator for effecting a pre-cooling and an after-heating of the air.

A still further feature of the present invention is the provision of a refrigerating plant including an evaporator disposed in the path of the air movement, means associated with a refrigerating plant for producing a pre-cooling and an after-heating of the circulating air, and further heat exchange devices for effecting a pre-cooling and an after-heating independently of the refrigerating plant.

Still another feature of the present invention is the provision of means for employing a supply of cool water in multiple flow for effecting the condensation of refrigerant gas in the condenser of the aforesaid refrigerating plant and for pro-

ducing a first or initial pre-cooling of the air on its way to the evaporator surfaces.

Still another feature of the present invention is the provision of such air-conditioning apparatus in conjunction with automatic control devices for determining the rate of heat exchange between the pre-cooling and the after-heating devices.

With these and other features as objects in view, as will appear more clearly in the course of the following specification and claims, an illustrative form of practicing the invention is set out on the accompanying drawing, which conventionally and diagrammatically shows elements of construction and their assemblage according to the present invention.

In the drawing, the apartment 10, for which the air is to be conditioned, is connected by an outlet duct 11, with a conduit 12 which in the illustrative apparatus is formed as a structure enclosing the various cooling, heating and eliminating devices which are interposed in the path of flow of the circulating air. After passing through these devices, the air is moved by a fan 13, driven by the motor 14, through an admission duct 15 back into the apartment 10, thus establishing the circulation of air.

A refrigerating plant is illustrated as comprising a compressor or compressors 16 capable of variable action for delivering definite quantities of hot compressed refrigerant gas, according to its adjustment. This compressed gas passes into a condenser 17 in which it is liquefied and moves to a sub-cooler 18 for the refrigerant liquid, this subcooler having its heat exchanging walls disposed in the path of the flow of air through the conduit 12 so that the hot refrigerant liquid is cooled by the air on its way through the conduit 12 back to the apartment 10, and conversely the heat from this liquid is employed for warming the air. The cooled liquid now passes to the expansion valve 19 and thence into the evaporator 20 which likewise has heat-exchange walls disposed in the path of the air moving through the conduit 12, so that this evaporator operates to produce a predetermined minimum temperature of this air. From the evaporator 20, the refrigerant gas escapes and passes through a superheater 21 on its way back to the compressor 16. This superheater 21 is likewise disposed in heat exchange relationship with the air flowing through the conduit 12, so that this air is precooled before it passes into the evaporator 20 on the one hand, and on the other hand the refrigerant gas is superheated and all liquid content

thereof is volatilized before passing to the compressor 16. It will be noted that this establishes a refrigerating plant with the several parts connected for performing multiple operations upon the air during its passage in the conduit 12.

The condenser 17 is illustrated as being controlled by cold water coming from a source of supply by a conduit 22, and which is utilized under control of the valve 23 in a spray device 24, by which the water is caused to flow over the condenser 17. The water from the condenser is caught in a sump 25 and then passes to a discharge or waste passage 26. A branch of this cold water supply pipe 22 also communicates with a valve 27 so that cold water may also be passed through a precooler 28 comprising a coil, for example, traversed by this cold water, which escapes from the cooler 28 into the waste pipe 25.

A further heat exchange system, independent 20 of the refrigerating plant, is shown as comprising a circulating pump 30 for moving the exchange medium, which is preferably water or brine by reason of the large heat capacity of aqueous fluids. This heat exchange medium 25 passes by conduit 31 into the heat exchanger 32 where the warm water causes a warming of the air passing through conduit 12, and is itself cooled. The cooled water passes by conduit 33 into the heat exchanger 34 where it serves to 30 cool the air on its way to the evaporator 20, and is itself warmed thereby, so that warm water returns by conduit 35 to the pump 30.

The operation of the precooling devices 28, 21, and 34 causes a successive reduction of the temperature of the air, and this is finally brought to a predetermined minimum by the operation of evaporator 20. As a result, the circulating air is reduced to a temperature below its dew point so that water precipitates therefrom and forms 35 suspended globules and also collects on the walls of conduit 12 and of the devices themselves and flows down and is discharged. The suspended globules are removed from the air current by an eliminator 36 which is shown conventionally. 40 Thereafter, the cold dry air is successively heated by the devices 32 and 18. If a sufficient heating is not afforded thereby, a higher temperature is produced by the radiator device 37 which is supplied through a control valve 38 with steam coming from a steam main 39. This steam valve 38 is actuated by a thermostatic device 40 which is controlled through conduit 41 from the thermostat 42.

As it is usually desirable to permit the escape 55 of a portion of the circulating air, and to replace this portion by an admission of fresh air, an exhaust duct 43 may be utilized in conjunction with the regulator damper 44, while fresh air is admitted through a duct 45 under control 60 of a damper 46. The two dampers may be coordinated in their action as by a connecting link 47.

It is preferred to provide a type of automatic control for the apparatus. In the illustrated 65 form, a hygostat 50 is connected by conduit 51 with the driving device 52 which turns a shaft upon which are mounted the contact sectors 53, 54, 55, and 56. These contact sectors have varying angles and cooperate respectively with the brushes 57, 58, 59, and 60. Current is supplied 70 from a main conductor 61 through a switch 62 to conductor 63 and thus to the brush 57 which remains in contact with the sector 53 regardless of the position of the several sectors. Sector 53 75 is electrically connected to all of the other sec-

tors so that current is continuously supplied thereto so long as switch 62 is closed. When the hygostat 50 indicates an extremely dry condition, the brush 58 does not engage the sector 54, and brushes 59 and 60 are likewise free of their sectors 55 and 56. The operation of the plant is now essentially static, and comprises a circulation of air by the fan 13.

When the moisture content of the air increases above the desired percentage, the hygostat 50 causes such a movement of the sectors that current flows from sector 54 by brush 58 and conductor 64 to the circulating pump 30 and starts this pump. If the refrigerating system is entirely static, no result occurs, but if 15 the evaporator is still cool from a prior refrigerating cycle, the air issuing from it cools the heat exchanger 32 and thus a cooling is effected at the heat exchanger 34 and thus a slightly greater cooling is effected of the volume of air circulating 20 through the conduit 12 and a slight elimination of moisture occurs therefrom.

If this does not suffice and the hygostat 50 continues to indicate an excessive moisture, a contact is established by the further rotation of 25 the sectors so that sector 55 causes current to flow to brush 59 and by conductor 66 to the control device 67 of the compressor 16 and the latter comes into operation for compression at a fraction of its maximum capacity, and thus the 30 refrigerant plant as a whole comes into action and the evaporator 20 passes to a lower temperature, below the dew point of the air moving through conduit 12, and moisture is eliminated 35 therefrom. During this phase of the cycle, it will be noted that the refrigerant medium is employed at sub-cooler 18 for warming the air on its way back to the apartment 10, that it is employed in the evaporator 20 for producing the 40 minimum temperature of circulating air, and that the returning quasi-gaseous or gaseous refrigerant is employed in the super-heater device 21 for pre-cooling this circulating air.

Meanwhile, the circulating pump 30 continues 45 to run and serves for heating the air on its way from the evaporator back to the apartment 10, and for employing usefully the "cold" withdrawn from this returning air as a means of 50 pre-cooling the air before passing to the evaporator 20, through the agency of the heat exchanger 34.

If this operation of the compressor 16 at fractional capacity is still insufficient for establishing the desired dehumidification, the sectors are turned yet further under the control of the 55 hygostat 50 so that a contact is made at sector 56 for the flowing current by brush 60 and conductor 68 to the control device 69 of the compressor 16 and the latter comes into action at full capacity. Thereby a greater refrigeration 60 effect is produced for cooling the air and thus establishing a very low dew point thereof, together with an efficient exchanging of heat between the air at the two stages of its movement through the conduit 12.

It will be noted that the several electrical devices are connected with a return conductor 65 to complete the back flow of current.

It is obvious that if the air becomes drier than a pre-determined standard, the hygostat 50 causes a reverse operation of the driving device 52 so that the sectors successively open the paths for current to their corresponding brushes 60, 59, and 58.

It is obvious that the invention is not limited 75

to the particular employment illustrated, but that it may be employed in many ways within the scope of the appended claims.

Having thus described my invention, what I claim is:

1. An air conditioning apparatus including means providing a path of flow for the air; and a refrigerating plant having a compressor, a condenser, a refrigerant liquid subcooler, an expander, an evaporator, and a refrigerant gas superheater connected together; said superheater, evaporator and sub-cooler being located in heat exchange relation with the flowing air for successively producing a precooling, cooling and heating thereof; heat exchanging devices located upstreamward and downstreamward of the evaporator in said path of air flow, means for circulating an exchange medium through said heat exchange devices so that the upstreamward device exerts a cooling effect upon the flowing air and the downstreamward device exerts a heating effect thereon; said cooling device, said evaporator and said heating device being successively traversed by air flowing in said path; and means responsive to the humidity of the flowing air for controlling the circulation through said heat exchanging devices and for varying the output of said compressor, said responsive means being effective for establishing a maximum circulation through said heat exchanging devices before establishing a maximum output of said compressor.

2. An air conditioning apparatus including means providing a path of flow for the air, a refrigerating plant including a variable capacity compressor and an evaporator, heat exchanging devices located upstreamward and downstreamward of the evaporator, means for circulating an exchange medium through said heat exchange devices so that the upstreamward device exerts a cooling effect upon the flowing air and the downstreamward device exerts a heating effect thereon, said cooling device, said evaporator and said heating device being successively traversed by air flowing through said means, and means responsive to the humidity of the flowing air for controlling the circulation through said devices and for varying the output of said compressor, said responsive means being effective for establishing a maximum circulation through said heat exchanging devices before establishing a maximum output of said compressor.

3. An air conditioning apparatus including means providing a path of flow for the air; and a refrigerating plant having a compressor, a condenser, a refrigerant liquid subcooler, an expander, and an evaporator connected together; said evaporator and subcooler being located in heat exchange relation with the air flowing in said path for successively producing a cooling and a reheating thereof; heat exchanging devices located upstreamward and downstreamward of the evaporator, means for circulating a heat exchange medium through said heat exchange devices so that the upstreamward device exerts a cooling effect upon the flowing air and the downstreamward device exerts a heating effect thereon, said downstreamward device being located between the evaporator and the sub-cooler; said cooling device, said evaporator, said heating device and said subcooler being successively traversed by air flowing in said path; and means responsive to the humidity of the flowing air for controlling the circulation through said exchanging devices and for varying the effect of said

evaporator, said responsive means being effective for establishing a maximum circulation through said heat exchanging devices before securing the maximum effects from said sub-cooler and said evaporator.

4. An air conditioning apparatus including means providing a path of flow for the air; a refrigerating plant having a compressor, a condenser, a refrigerant liquid subcooler, an expander, an evaporator, and a refrigerant gas superheater connected together; said superheater, evaporator, and subcooler being located in succession downstreamward of one another in heat exchange relation with the air flowing in said path; a first heat exchange radiator located between the superheater and the evaporator in said path of flow, a second heat exchanger radiator located between the evaporator and the sub-cooler in said path of flow, and liquid circulating means for moving liquid through and between 20 said radiators.

5. An air conditioning apparatus including means providing a path of flow for the air; a refrigerating plant having a compressor, a condenser, an expander, and an evaporator connected together, said evaporator being located in heat exchange relation with the air flowing in said path; a first radiator located upstreamward of the evaporator, a second radiator located downstreamward of the evaporator, and liquid moving means for maintaining the flow through and between said radiators; a device responsive to the condition of humidity of the air moving in said path, means controlled by said responsive device for controlling the operation of said liquid 35 moving means for determining the amount of water separated from the moving air, and means also controlled by said responsive device for changing the refrigerating effect at said evaporator, said controlled means being coordinately actuated so that a maximum operation of said liquid moving means is produced before a maximum cooling effect is produced in said evaporator.

6. An air conditioning apparatus including means providing a path of flow for the air, a refrigerating plant having a compressor of variable capacity, a condenser, an expander, and an evaporator connected together, said evaporator being located in heat exchange relation with the air flowing in said path; a first radiator located upstreamward of the evaporator, a second radiator located downstreamward of the evaporator, and liquid moving means for establishing a circulation of liquid through and between said radiators, a device responsive to the humidity of the air moving in said path, and means controlled by said responsive device for successively controlling said liquid moving means and said compressor and operating when a minor dehumidification is to be accomplished for energizing said liquid moving means and operating when successively greater dehumidifications are to be accomplished for starting the compressor and for effecting the operation of the same at full capacity.

7. An air conditioning apparatus including means providing a path of flow for the air; a refrigerating plant including a compressor of variable capacity, an evaporator, and a refrigerant liquid sub-cooler, said evaporator and sub-cooler being successively traversed by air flowing through said means; heat exchanging devices located upstreamward and downstreamward of the evaporator in the path of the air flowing

therethrough, means for circulating an exchange medium through said heat exchange device so that the upstreamward device exerts a cooling effect upon the flowing air and the downstreamward device exerts a heating effect thereon; said cooling device, said evaporator and said heating device being successively traversed by air flowing through the same; and means responsive to

the humidity of the flowing air for controlling the circulation through said heat exchanging devices and for varying the output of said compressor, said responsive means being effective for establishing a maximum circulation through said exchanging devices before establishing a maximum output of said compressor. 5
